[57] CLAIM

The ornamental design for the jug for coffee or milk, as shown and described.

DESCRIPTION

FIG. 1 is a front elevational view of a jug for coffee or milk showing my new design;

FIG. 2 is a right side elevational view thereof;

FIG. 3 is a left side elevational view thereof;

FIG. 4 is a rear elevational view thereof;

FIG. 5 is a top plan view thereof; and,

FIG. 6 is a bottom plan view thereof.

The pattern visible in FIG. 5 is continuous, and does not contain a break. The break visible is caused by a reflection.
